UNITED STATES PATENT OFFICE.

ALEXIS L. LAMAR, OF PITTSBURG, KANSAS.

KEROSENE-VAPORIZER.

1,222,548.

Specification of Letters Patent. Patented Apr. 10, 1917.

Application filed July 15, 1916. Serial No. 109,437.

To all whom it may concern:

Be it known that I, ALEXIS L. LAMAR, a citizen of the United States, residing at Pittsburg, in the county of Crawford and State of Kansas, have invented certain new and useful Improvements in Kerosene-Vaporizers; and I do hereby declare the following to be a full, clear, and exact description of the invention, such as will enable others skilled in the art to which it appertains to make and use the same.

This invention relates to vaporizers, and more particularly to a kerosene vaporizer for an internal combustion engine.

15 The principal object of the invention is the provision of a device of the above stated character, whereby the kerosene is efficiently vaporized so as to produce a highly combustible gas.

20 Another object of the invention is the provision of a device embodying an intake manifold having an exhaust manifold arranged therein, whereby the heat of the exhaust gases from the engine will be sufficient to completely and readily vaporize the kerosene passing through the intake manifold.

25 A further object of the invention is the formation of heat radiating pins on the interior surface and exterior surface of the exhaust manifold, whereby a greater radiation of heat may be accomplished.

30 A further object of the invention is the provision of means for introducing gasoline into the intake manifold for an initial starting of the engine.

35 And a still further object of the invention is the provision of means for introducing a stream of water of any preferred size within the intake manifold.

40 With these and other objects in view as will appear as the description proceeds, the invention comprises the various novel features of construction, combination and arrangement of parts as will be more fully described hereinafter and set forth with particularity in the appended claims.

Referring to the drawings,

Figure 1 is a detail perspective view of 45 my improved kerosene vaporizer attached to an ordinary four cylinder engine block.

Fig. 2 is a vertical longitudinal sectional view through the vaporizer, showing a conventional form of kerosene carburetor attached thereto.

Fig. 3 is a horizontal sectional view taken on line 8—3 of Fig. 2.

Fig. 4 is a detail elevation of a portion of the attaching means, and

Fig. 5 is a detail elevation of the remaining portion of the attaching means.

Similar characters of reference are used to denote like parts throughout the accompanying drawings and the following description.

Referring more particularly to the drawings, my improved kerosene vaporizer is shown to consist of a kerosene intake manifold 1, which comprises in this instance, a horizontally disposed cylindrical manifold 70 pipe 2, which has an angular extension 3 that extends downwardly below the manifold pipe 2 in angular relation thereto.

Disposed longitudinally through the intake manifold 2 is an exhaust manifold 4 75 which projects beyond the end 5 of the intake manifold a suitable distance where the end is closed, as clearly indicated by the reference numeral 6. The opposite end of the exhaust manifold extends beyond the 80 opposite end 7 of the intake manifold a suitable distance and then extends downwardly at an angle to form an extension 8. A suitable pipe, not shown, is connected to this extension 8 and leads to the muffler of 85 the engine. The exhaust manifold 4, which is horizontally disposed through the intake manifold, is provided with an outlet exhaust pipe extension 9 and, extends downwardly through the center of the extension 90 3 of the intake manifold. This extension 9 extends through the extension 3 to a point beyond the end 10 thereof.

A butterfly valve 11 is arranged in the extension 9 below the lower end 10 of the 95 intake manifold and is provided with a bell crank arm 12 to which may be connected a pull rod, not shown, whereby the butterfly valve 11 may be opened to allow the exhaust gases to pass through the extension 100 9 to the atmosphere. Connected to the extension 3 of the intake manifold is a kerosene intake pipe extension 13, which in this instance, is formed integral with the section 3. Any suitable or well known form 105 of kerosene carburetor, such as conventionally shown and indicated by 14, may be used and connected to the intake pipe extension 3, and connected to this kerosene carburetor 14 is a supply pipe 15 which 110

leads to the carbureter from any suitable source or supply, not shown.

The horizontally disposed portion of the exhaust manifold arranged within the intake manifold 2, and the angularly and downwardly extending extension 9 arranged within the extension 3, are formed with heat radiating pins 16 on the outer and inner surfaces of the manifolds.

10 While I have shown these heat radiating pins formed and arranged on both the inner and outer surfaces of the exhaust manifold pipes, I desire to have it understood that if desired, they may be formed and used on 15 either one of the inner or outer surfaces of the exhaust manifold pipes. By the provision of these heat radiating pins, it will be manifest that as the exhaust gases pass into the exhaust manifold 4 and the extension 9 thereof that these pins will become very hot, and as a result, radiate a great deal more heat within and around the exhaust manifolds to more efficiently vaporize the kerosene in the intake manifold around the extension 9.

20 The horizontally disposed intake manifold 2 is formed with nipples 16' that are designed to seat within the intake openings 17 of the engine cylinders 18. These nipples are provided with outlet openings 19, 30 through which vaporized gases pass or enter the engine.

The exhaust manifold pipe 4 is formed with nipples or extensions 20 that extend through the intake manifold 2 and communicate with the interior of the exhaust manifold 4. These nipples 20 are also seated in the exhaust openings 21 of the engine cylinders 18. Additional nipples 22 are formed integral with the exhaust manifold 4 at points beyond and adjacent the opposite ends of the intake manifold 2, and likewise have their outer ends seated within the exhaust openings 21 of the engine cylinders.

45 In order to attach my improved kerosene vaporizer to the engine cylinders, I employ in this instance, T bolts 23 that have the outer ends of the stems 24 threaded and passed through bores formed between the cylinders of the engine and are secured there- 50 in by the nuts 25 threadedly connected to their ends. Each of the T-bolts 23 is formed with a head 26 having perforations 27 at its opposite end and through which are designed to pass the threaded ends of U-bolts 55 28, which latter are secured in place by nuts 29 threadedly connected to the ends of the U-bolts.

While I have shown two of these fastening or securing means, in Fig. 1 of the 60 drawings, it is to be understood that any desired number of these securing means may be employed to rigidly and firmly hold the vaporizer in position.

Tapped into or threadedly connected with 65 the intake manifold extension 3 is a valve

30 which is provided with a valve stem 31 that is designed to extend upwardly to the automobile dash within easy reach of the driver. Connected to this valve 30 is a gasoline pipe 32. By the use of this valve 70 an initial supply of gasoline may be allowed to enter the intake manifold to give the engine an initial start. In starting the engine, gasoline is admitted through this valve 30 on which to run the motor until the exhaust pipe has become sufficiently heated by the passage of the burnt gases therethrough, to thoroughly vaporize the kerosene that is being sucked into the intake manifold from the carbureter 14. When the 80 exhaust pipes have become sufficiently heated to thoroughly vaporize the kerosene, the valve 30 is closed, whence it will be seen that the engine will run entirely upon the kerosene vapor or gas.

85 A valve 33 is tapped into or threadedly connected to the intake manifold 2 and is provided with a valve stem 34 that extends upwardly to the dash of the automobile within easy reach of the operator. A water pipe 35 is connected to this valve which leads to the valve from any suitable source of supply. By the provision of this valve 33, it will be apparent that a stream of water of any desired size may be introduced 90 into the intake manifold of the vaporizer, where it will be instantly converted into steam for commingling with the vaporized kerosene and hot air. This steam will not only help to more thoroughly vaporize the 95 kerosene within the intake manifold but will to a great extent assist in the removal of any carbon that may be within the engine cylinder and also prevent the rapid accumulation of carbon in the cylinders.

100 In the operation of the device and in the initial starting of the engine, the valve 30 is opened which will permit of the desired amount of gasoline entering the intake manifold with which to run the engine until the engine has been run sufficiently to cause 110 the burnt exhaust gases to heat the exhaust manifold to such a degree of temperature as to readily and quickly vaporize the kerosene surrounding it that is being sucked in from the carbureter, after which the valve 30 is closed, thus cutting off the supply of gasoline and permitting the motor to run entirely upon the kerosene vapor or gas that is being sucked in from the carbureter.

115 By the construction shown and described it will be apparent that my improved form of kerosene vaporizer will be equally as effective in operation, when the motor is traveling up a hill as it will when it is traveling 125 on a level, for if it is desired to climb a hill the butterfly valve 11 may be opened so as to allow the exhaust gases to exhaust directly to the atmosphere without having to pass through the muffler of the machine, the ex- 130

haust gases in passing through the outlet extension 9 heating the pins 16 so that they will radiate their heat in all directions around the interior of the intake manifold 5 sufficiently to vaporize the kerosene that is being sucked in from the intake pipe 13 to the intake manifold section or extension 3. Thus it will be seen that a complete and efficient vaporization of the kerosene may be 10 had, in the operation of the device, by the exhaust gases passing either through the main exhaust pipe or the outlet extension 9 to the atmosphere.

What I claim is:—

- 15 1. An engine manifold comprising an intake manifold consisting of a horizontally disposed manifold pipe, and an extension pipe extending downwardly from the horizontal section, a hydrocarbon intake pipe connected to the lower end of said depending extension, said intake manifold being provided with outlet openings, an exhaust manifold disposed through and within the intake manifold in spaced relation to the walls 20 thereof, an exhaust pipe extension disposed through and in spaced relation to the walls of the depending section of the intake manifold, and a valve arranged in the lower end of said exhaust pipe extension adapted to 25 control the heat radiating efficiency of the exhaust manifold within the intake manifold.
2. An engine manifold comprising an intake manifold having outlet openings therein, an extension pipe projecting from said intake manifold, a hydro-carbon supply pipe connected to said extension, an exhaust manifold disposed through and in spaced 30

relation to the walls of the intake manifold inlet, arms projecting laterally from the exhaust manifold through said intake manifold, and exhaust pipe extension extending through and in spaced relation to the walls of the intake extension, and heat radiating means carried by said exhaust manifold and 40 exhaust extension pipe.

3. An engine manifold comprising an intake manifold, consisting of a horizontally disposed manifold, and an extension pipe extending downwardly from said horizontal manifold, a hydrocarbon intake pipe connected to the lower end of said depending extension, said intake manifold being provided with outlet openings, an exhaust manifold disposed through and in spaced relation 45 to the walls of the intake manifold, an exhaust pipe extension disposed through and in spaced relation to the walls of the depending section of the intake manifold, heat radiating pins disposed on the inner and outer surfaces of the exhaust manifold and the exhaust depending section, and a valve arranged in the lower end of said exhaust pipe depending section, adapted to be actuated to control the heat radiating efficiency 50 of said exhaust manifold, exhaust depending section, and heat radiating pins carried thereby.

In testimony whereof I have signed my name to this specification in the presence of 70 two subscribing witnesses.

ALEXIS L. LAMAR.
